UNITED STATES PATENT OFFICE.

HARVEY H. BLACKMAN, OF ITHACA, NEW YORK, ASSIGNOR TO CORNELL INCUBATOR MFG. CO., OF ITHACA, NEW YORK, A CORPORATION OF NEW YORK.

INCUBATOR.

No. 806,098.

Specification of Letters Patent.

Patented Dec. 5, 1905.

Application filed May 17, 1904. Serial No. 208,877.

To all whom it may concern:

Be it known that I, HARVEY H. BLACKMAN, a citizen of the United States of America, residing at Ithaca, in the county of Tompkins and State of New York, have invented certain new and useful Improvements in Incubators, of which the following is a specification.

This invention relates to improvements in incubators, and is more especially in the nature of an improvement in that type of incubator illustrated and described in United States Letters Patent to E. W. Andrews, dated October 1, 1901, No. 683,830.

The present invention has for its object the provision of an incubator wherein a more uniform temperature in all parts of the egg-chamber may be obtained and also by which more perfect ventilation in the egg-chamber may be effected by the feeding of fresh air in proper proportions thereto, thus enabling the atmospheric conditions of the egg-chamber to meet the necessary requirements and insuring a maximum percentage in the hatching of the eggs.

The invention also contemplates an arrangement of the structural elements of the incubator whereby fresh air may be properly mixed with the heated air, so that when the admixture passes into the egg-chamber there will be no deleterious results occasioned by the chilling of the eggs in course of incubation.

With these general objects in view and others which will appear as the nature of the improvements is better understood the invention consists, substantially, in the novel construction, combination, and arrangement of parts, as will be hereinafter fully described, illustrated in the accompanying drawings, and pointed out in the appended claims.

While the form of the invention herein shown and described is what is believed to be a preferable embodiment thereof, it will of course be understood that the same is susceptible of various changes in the form, proportion, and minor details of construction, and the right is therefore reserved to modify or vary the invention as falls within the spirit and scope thereof.

In the drawings, Figure 1 is a sectional perspective view of an incubator constructed in accordance with the present invention, parts thereof being broken away to more clearly

illustrate the relative arrangement of the internal parts, the screen illustrated in Fig. 2 being also omitted for clearness. Fig. 2 is a longitudinal sectional view thereof through the combustion-flue. Fig. 3 is a detail perspective view of the air-distributer. Fig. 4 is a similar view of another form thereof.

Referring in detail to the drawings, the numeral 1 designates the usual incubator-box, the same being formed of separated internal and external walls 2 and 3, respectively, thus providing air-spaces between said walls. It may be stated, however, that the air-spaces at the sides of the box 1 do not communicate with the others, but merely perform the function of insulators. The internal walls 2, bottom 2', and top of the incubator form between them an inclosure used as an egg-chamber.

Extending longitudinally of the box structure 1 is a combustion-flue 4, one end of which communicates with the combustion-chamber 5' of a generating-lamp or heater 5, which latter may also be of the type illustrated in the Andrews patent hereinbefore referred to. It will thus be seen that the products of combustion pass from said lamp through the flue 4, and thus the radiation from said flue will tend to heat the surrounding air within the box 1. Encircling the flue 4 is a hot-air flue 6, said flue connecting with the hot-air chamber 6' of the generator 5 and terminating at the adjacent end wall of the internal structure 2, so that the air as it passes through the heater will take up a certain percentage of the heat generated thereby and attain the temperature which may be necessary for incubation. It will be observed, however, that the inner end of the hot-air flue 6 passes horizontally through an opening in the internal end wall 2, the opening extending some distance below the bottom of the flue, so that a passage 7 is thus provided which permits entrance of air from the space between said end wall and the adjacent outer end wall, this air-space being designated by the numeral 8 and being fed with atmospheric air through a series of openings 9, formed at the bottom of said space. Consequently as the fresh air is drawn in through the openings 9 the same rises and feeds through the opening 7, as will be hereinafter more fully stated. It will be noted that the space 8 does not communicate

100
105

with the space at the bottom of the structure.

Surrounding the combustion-flue 4 and the inner end of the hot-air flue 6 is an air-distributer 10, which distributer is in the form of a rectangular flared box, the smaller end of which is suitably connected to the inner end wall 2 to receive the heated air and the fresh air from the flue 6 and the passage 7, 5 said smaller end of the distributer 10 being of larger area than the combined area of the flue 6 and said passage 7. By referring to Fig. 3 it will be observed that the distributer 10 is provided with an elongated equalizer 11, the width of which equalizer is approximately only one-half of the entire width of the mouth of the distributer 10, and the function of said equalizer is to prevent a proportion of the air passing through 10 the distributer 10 immediately falling from the mouth thereof into the egg-chamber, but to conduct the same to a point toward the opposite end of said chamber, while the other portion of the air not so acted upon by the 15 equalizer will gravitate as soon as it leaves the mouth of the distributer 10. Thus a portion of the air fed by the distributer 10 will enter the egg-chamber at one end thereof, while the other portion traverses the 20 surface of the equalizer 11 and does not enter the egg-chamber until it reaches the end of said equalizer.

The end wall 2 next adjacent the air-space 8 is also provided with a plurality of feed- 25 openings 12, which communicate with the air-space 8, said openings being arranged in a plane below the passage 7, so that air may be taken directly from the passage 8 and introduced into the egg-chamber. The bottom of the latter is also provided with a series of perforations 13, which communicate with the space immediately below said egg-chamber, and said space likewise communicates with an air-space 14, arranged at the 30 end of the box 1 opposite to the air-space 8, an exit-opening 15 being arranged in the adjacent outer end wall of the box 1 and controlled by a suitable slide 16 for regulating the size of said opening. Through the medium of the slide 16 it will be seen that the 35 amount of air passing through the opening 15 to the atmosphere may be controlled.

In Fig. 4 is illustrated another form of the distributer 10; but this form is substantially 40 the same as that illustrated in the other figures of the drawings except that the bottom of the distributer is elongated and extends to a point beyond the free edge of the top of the distributer and is connected thereto by side 45 flanges 17. The purpose of this form is to cause the air introduced to the egg-chamber to be projected to a point nearer the opposite end thereof from that wherein it is introduced.

60 65 A screen 18, as illustrated in Fig. 2, is ar-

ranged beneath the flue 4 and distributer 10, whereby the descending air may be effectually subdivided into fine streams.

In the operation of the incubator it will be observed that the hot air passes therein through the flue 6 and discharges into the distributer 10. The entrance of the hot air into the distributer 10 creates a suction therein, thus drawing fresh air through the openings 9 into the air-space 8 and through the passage 7 into the distributer. This fresh air at once commingles with the hot air discharged by the flue 6, thereby tempering the hot air, and the admixture thus formed discharges through the open end of the distributer 10 and passes into the egg-chamber. The air thus entered gravitates through the egg-chamber and passes through the openings 13 into the space below, whence it issues into the space 14 and ultimately discharges through the opening 15 to the atmosphere. Fresh air will also enter through the openings 12, and through the arrangement described it will be seen that a uniform temperature in all parts of the egg-chamber is obtained and perfect ventilation therein insured. The fact that the fresh air mixes with the hot air in the distributer 10 prevents chilling of the eggs, and consequently a maximum percentage in the hatching of the eggs is assured.

Having thus described the invention, what is claimed as new, and desired to be secured by Letters Patent, is—

1. In an incubator, the combination with the body thereof comprising inner and outer walls spaced from each other to provide communicating air-spaces at one end and the bottom of said body, the latter having at its opposite end a fresh-air space which communicates with the atmosphere, the space within said inner walls forming an egg-chamber, of a hot-air flue projecting through said fresh-air space and passing horizontally through an opening in the inner wall of the fresh-air space, the opening extending some distance below the bottom of the flue to form an air-passage which communicates with the aforesaid fresh-air space, and an air-distributer arranged within the egg-chamber and surrounding the mouth of the hot-air flue and the air-passage immediately therebeneath, whereby the hot air fed by said hot-air flue and the fresh air introduced from said fresh-air space are caused to mix in the distributer and be discharged by the latter into the egg-chamber.

2. In an incubator, the combination with the body thereof comprising inner and outer walls spaced from each other to provide communicating air-spaces at one end and the bottom of said body, the latter having at its opposite end a fresh-air space which communicates with the atmosphere, the space within said inner walls forming an egg-chamber, of

a hot-air flue projecting through said fresh-air space and passing horizontally through an opening in the inner wall of the fresh-air space, the opening extending some distance 5 below the bottom of the flue to form an air-passage which communicates with the aforesaid fresh-air space, and an air-distributer arranged within the egg-chamber and surrounding the mouth of the hot-air flue and the air-passage immediately therebeneath, whereby the hot air fed by said hot-air flue and the fresh air introduced from said fresh-air space are caused to mix in the distributor and be discharged by the latter into the egg-chamber, said distributor having an elongated equalizer to cause the air introduced into the egg-chamber to gravitate at different points therein.

3. In an incubator, the combination with the body thereof comprising inner and outer walls spaced from each other to provide communicating air-spaces at one end and the bottom of said body, the latter having at its opposite end a fresh-air space which communicates with the atmosphere, the space within said inner walls forming an egg-chamber, of a hot-air flue projecting through said fresh-air space and passing horizontally through an opening in the inner wall of the fresh-air space, the opening extending some distance below the bottom of the flue to form an air-passage which communicates with the aforesaid fresh-air space, and an air-distributer arranged within the egg-chamber and surrounding the mouth of the hot-air flue and the air-passage immediately therebeneath, whereby the hot air fed by said hot-air flue and the fresh air introduced from said fresh-air space are caused to mix in the distributor and be discharged by the latter into the egg-chamber, the bottom of the egg-chamber be-

ing perforated to establish communication between said chamber and the space immediately therebeneath, whereby the air in the egg-chamber will be exhausted in the space 45 beneath the same and discharged to the atmosphere through the end air-space in communication with said bottom space.

4. In an incubator, the combination with the body thereof comprising inner and outer walls spaced from each other to provide communicating air-spaces at one end and the bottom of said body, the latter having at its opposite end a fresh-air space which communicates with the atmosphere, the space within 50 said inner walls forming an egg-chamber, of a hot-air flue projecting through said fresh-air space and passing horizontally through an opening in the inner wall of the fresh-air space, the opening extending some distance 55 below the bottom of the flue to form an air-passage which communicates with the aforesaid fresh-air space, and an air-distributer arranged within the egg-chamber and surrounding the mouth of the hot-air flue and the air-passage immediately therebeneath, whereby the hot air fed by said hot-air flue and the fresh air introduced from said fresh-air space are caused to mix in the distributor and be discharged by the latter into the egg-chamber, the inner end wall being provided at a point below said distributor with a series of feed-openings which communicate directly with the fresh-air space for introducing fresh air into the egg-chamber.
